A. LENORMAND

TONGS

Filed Oct. 26, 1925

INVENTOR

ALFRED LENORMAND

By Lincoln Johnson

ATTORNEY

UNITED STATES PATENT OFFICE.

ALFRED LENORMAND, OF SAN FRANCISCO, CALIFORNIA.

TONGS.

Application filed October 26, 1925. Serial No. 64,784.

To all whom it may concern:

- Be it known that I, ALFRED LENORMAND, a citizen of the United States, and a resident of the city and county of San Francisco, State of California, have made a new and useful invention—to wit, Improvements in Tongs; and I do hereby declare the following to be a full, clear, concise, and exact description of the same.
- 10 This invention relates particularly to a device adapted to be used for pulling and twisting the reinforcing wires used in cribbings, molds and other reinforced concrete construction forms.
- 15 An object of the invention is to provide a tongs, or pincers, provided with jaws for gripping the loose ends of a reinforcing wire, and with a cam member by means of which the operator may apply a pulling pressure to the said wires.
- 20 A further object of the invention is to provide a wire pulling tongs having adjustable jaws thereon that will be superior in point of simplicity, inexpensiveness of construction, positiveness of operation, and facility and convenience in use and general efficiency.
- 25 Other objects and advantages will appear as this description progresses.
- 30 In this specification and the annexed drawings, the invention is illustrated in the form considered to be the best, but it is to be understood that the invention is not limited to such form, because it may be embodied in other forms, and it is also to be understood that in and by the claims following the description, it is desired to cover the invention in whatsoever form it may be embodied.
- 35 In the accompanying one sheet of drawings,

Fig. 1 represents a side elevation of a tongs constructed in accordance with my invention applied in the initial operating position to the reinforcing wires on a concrete form.

Fig. 2 is a view similar to Fig. 1 showing the tongs in the pulling position.

Fig. 3 is an enlarged side elevation of my tongs.

Fig. 4 is a plan view of Fig. 3.

Fig. 5 is an end elevation of Fig. 3.

In reinforcing concrete construction work the forms or molds, into which concrete is poured, are usually held together in a more

or less stable and permanent manner, yet so arranged that the boards of the form or mold may be quickly and easily taken from the molded concrete after it has hardened. It is almost a universal practice to utilize 60 wires, tied around the sheathing and studs of the molds, to hold the parts together. The work of tying the parts of the mold together by means of the wires is exceedingly difficult and complicated with the 65 forms of apparatus now employed to attain this end.

In my invention I have provided a tongs, or pincer device, formed of a pair of complementary handle members 1 and 2, cross-pivoted at 3. The ends 4 and 5 of the tongs, opposite the respective handle portions 1 and 2 are arranged in spaced relation so as to provide a gap therebetween. The end 4 on the handle member 1 terminates as a curved 70 cam 6, for the purposes to be hereinafter described in detail. On the upper face of the end 4 I provide a jaw member 7 consisting of a flat, bar member extending outwardly on opposite sides of the end 4. The 75 jaw 7 is pivotally connected to the end 4 by a bolt 8 which allows the said jaw to turn within a limited radius about said end 4. On the contiguous, inside face of the end 5, of the other handle member 2 I provide a 80 companion jaw 9 pivoted by the bolt 10 to the end 5. The jaw 9 is substantially of the same size as the jaw 7 and is provided with flanged ends 11 and 12 into which the jaw 7 can be received. Each of the opposite ends 85 of the jaws 7 and 9 are loosely connected together by bolts or rivets 13 and 14. The opposite ends of the rivets 13 and 14 are peaned over and sufficient space provided between the head ends of the bolts 13 and 14 to 90 allow for spreading movement of the respective jaws 7 and 9, when the ends of the said tongs are spread apart.

In Fig. 3 I have shown the handles separated, which spreads the opposite ends thereof proportionately, and in turn the jaws 7 and 9 are opened a distance sufficient to receive the ends of the reinforcing wire 15 therein.

In Fig. 1 I have shown a crude form of 105 concrete mold, consisting of the upright studs 16 and 17 arranged in spaced relation and with the sheathing boards faced along the outside of the stud 17. The wire 15 is wrapped around the boards 18 and the ends 110

of the said wire passed around the stud 16 an allowed to protrude therebeyond. The operator, in order to pull the reinforcing wire 15 taut, engages the ends of the said wire 5 with the jaws on the tongs and securely clamps the said ends therebetween. The operator then bears down on the handle members 1 and 2, exerting sufficient leverage thereon to force the cam member 6 against the face of the stud 16 which action pulls the reinforcing wire 15 taut. After the wire 15 has been pulled as tight as desired, the operator then rotates the tongs so as to twist the ends of the wire 15 together to form a 10 knot of sufficient tightness to hold the sheathing boards 18 in a fixed position on the studs. I have demonstrated that by using a tongs constructed in accordance with my invention, that it is possible for an operator to 15 pull and tie the ends of a reinforcing wire together in thirty (30) or forty (40) seconds time, whereas to do the same work by means of conventional forms of apparatuses now employed to do this work, it takes an operator at least two (2) minutes. My 20 invention greatly simplifies the method of tying the reinforcing wire ends together, and at the same time produces a more rigid mold than that which can be obtained by the older methods.

Having thus described this invention,

what I claim and desire to secure by Letters Patent is:—

1. A device such as described comprising a pair of complementary handle members cross-pivoted together; a jaw member pivotally mounted on the end of each of said handle members in co-operating relationship; and fastening means loosely connecting each of said jaws. 35

2. A device such as described comprising a pair of complementary handle members cross-pivoted together; a jaw member pivotally mounted on the end of each of said handle members in co-operating relationship; fastening means loosely connecting each of said jaws; and a cam member formed on the end of one of said handle members beneath the jaw portion thereon. 40

3. A device such as described comprising a pair of complementary handle members cross-pivoted together; a curved terminus on the end of one of said handle members; a pair of co-operating jaws pivotally related to each of the ends of said handle members, 55 one of said jaws having flanged ends thereon to receive the other jaw; and spacing bolts loosely connecting said jaw members. 50

In testimony whereof, I have hereunto set my hand at San Francisco, California, this 60 7th day of March 1925.

ALFRED LENORMAND.
